SEATING MEANS FOR WOOD CHIPPER
BED KNIVES

Charles A. Johnson, Berlin, N. H.

Application May 13, 1948, Serial No. 26,767

5 Claims. (Cl. 241—92)

1

This invention relates to wood chippers for use in cutting wood into chips for the purpose of making paper. More particularly it concerns a new and improved wood chipping machine having a retractable, adjustable and self-seating bed knife.

Wood chippers generally comprise revolvable knife members mounted on a disk rotating in a vertical plane, a fixed horizontal bed knife having a cutting edge cooperating with the moving blades to cut the chips and an inclined feed spout to direct a piece of wood by gravity against the cutting members at a suitable angle. The running clearance between the revolving and stationary knives should remain substantially constant for all lengths of chips being cut. It has been the practice to provide a bed knife firmly anchored and arranged to form a continuation of the lower end portion of the feed spout so that the wood will be fed smoothly into the cutting knives without any catapulting effect by reason of the moving blades tending to rotate the piece of wood about the upper surface of the bed knife as a fulcrum and throw the same out of alignment with the inner surface of the spout, and to vary chip length by adjusting the extension of the rotating knives from the disk and shifting the latter axially toward and away from the stationary knife.

Because of the great strains to which the various parts of the machine are subject it is important that the bed knife be rugged and firmly seated in the main frame and not permitted to work loose or vibrate. Furthermore it should be maintained constantly in a sharpened condition so that chips will be cut evenly and smoothly without the production of slivers and irregular pieces which do not digest properly for paper making. In prior art machines it has been found that easily retractable or adjustable bed knives will be insecurely held, while if they are firmly anchored they will be removable for sharpening purposes only after virtually complete dismantling of the machine. Since the knife should be sharpened frequently the machine will be shut down for unreasonably long periods for this purpose, or the operators may be tempted to run the same for excessive periods using a dull blade, with consequent production of a high proportion of defective chips.

It is an object of the present invention to provide in a wood chipper a new and improved bed knife and seat therefor whereby the knife may be quickly and easily withdrawn and replaced without need for extensive dismantling of the entire machine.

2

A further object of the invention is to provide an improved and easily retractable bed knife for a wood chipping machine in which the knife will be adjustable toward and away from the revolving knives as the latter are extended or retracted to vary chip lengths and nevertheless be firmly held in operative position.

Another object of the invention is to provide in a wood chipping machine a chipper knife base in which the knife will be self-seating and solidly held in proper spaced relation to the rotating cutting knives with the use of the minimum number of parts.

Further advantages and objects of the invention will become apparent from the following detailed description of a preferred embodiment thereof taken in connection with the accompanying drawings in which like numerals refer to like parts in several views and in which:

20 Fig. 1 is a front elevation of the novel wood chipping machine having a portion of the knife-carrying rotatable disc and one of the knives broken away to disclose the feed spout and bed knife structure therebehind;

25 Fig. 2 is a sectional view on line 2—2 of Fig. 1;

Fig. 3 is a plan view of the bed knife of the invention removed from the machine;

Fig. 4 is an elevation of the same; and

Fig. 5 is a section on line 5—5 of Fig. 4.

The machine of the invention comprises essentially a fixed main supporting frame 10, a rotatable disc 12 mounted on a shaft 14 and suitably driven by a driving mechanism (not shown).

35 The disc 12 carries four cutting knives 16 arranged adjacent corresponding slots 18 to permit passage of the wood chips therethrough. A feed spout 20 is supported in part on the base 10 by means of a supporting bracket 22 and is arranged at a suitable angle to feed the logs of wood against the rotating knives 16 in a manner well known in the art. The bracket 22 has a flat horizontal plate 24 adapted to be held firmly against the base plate 26 on the member 10 by means of bolts 28.

40 As most clearly seen in Fig. 2, the base member 10 is also provided with a laterally extending slot 30, the bottom face 32 of which slopes downwardly and rearwardly to receive and support the bed knife 34 of the invention with its upper and lower shims 32 and 46 respectively, the function of which will hereinafter be more fully explained. It will be seen that the bed knife 34 is readily insertable through the side of the machine and will be held in fixed relation therein by the weight of the spout 20.

In order to relieve the pressure caused by the weight of the feed spout 29 and its supporting bracket 22 to permit easy retraction and insertion of the knife 34, jack-screws 40 are provided in the plate 24 to bear against the plate 26, so as temporarily to remove the weight of the spout 29 and bracket 22 from the shims 52 to facilitate withdrawal of the bed knife 34 whenever desired.

The bed knife 34, as shown most clearly in Fig. 3, 4 and 5, consists of an integral piece of cast steel ground to provide a curved bevelled surface 42 which, when the knife is in place, constitutes a prolongation of the lower end portion of the inner surface 43 of the feed spout 29 so as to provide a smooth feed for the logs to be chipped without bouncing or vibration or the production of uneven chips or slivers because of irregularities in the feeding surface.

The bottom face 44 of the bed knife 34 is cut at a downwardly and rearwardly sloping angle so that the plane thereof is at an acute angle to the plane of the upper surface 38 whereby the knife will automatically seat itself in the slot 30, the surface 44 bearing against the surface 32 of the base and the knife being self seating by the mutual camming action of said surfaces. It is important that the base knife be solidly and firmly supported in its proper relation to the feed spout and the rotating knives to result in smooth and even chipping of the wood. It will be seen that by the mounting provided by the present invention the bed knife 34 will be solidly held when in operative position while at the same time provision is made for ready retraction and insertion thereof by the use of a single holding bolt 36 tapped into the plate 24. Endwise displacement of the knife 34 is prevented by the clamping action of the bolt 36. The bolt 36 is loosened at the same time as the jack screws 40 are operated to relieve the bed knife from the weight of the spout to permit withdrawal of the former.

In the art of wood chipping the so-called "chip length" is measured parallel with the wood fibers and is determined by the depth of the cut. Due to the oblique angle at which the log is presented to the knives by the spout 29, the chip length is somewhat greater than the distance from the cutting edges of the rotating knives 16 to the face of the disc 12. Appropriate adjustment or interchanging of the rotating knives 16 to vary the chip length may be accomplished in any manner well known in the art.

In order to vary the fore and aft adjustment of the bed knife to correspond with the chip lengths being cut at the particular setting of the rotating knives 16, a series of shims 46 may be detachably secured to the bottom surface 44 of the knife 34. Because of the slope of the cooperating rear surface 48 of the slot 30 and the bevelled face 49 of the bed knife 34, the raising up of the knife by the insertion of one or more shims 46 will cause the cutting edge 47 of the same to be adjusted forwardly toward the plane of the revolving disc 12, thus permitting shorter length chips to be cut without the necessity of shifting the disk 12 along its axis. When the knife is raised or lowered, the sloping curved surface 42, which forms an extension of the chipper spout, is either ground away or built up by welding so as to keep the same as a smooth continuation of the surface 43 of the spout. The sharp edge is built up of stellite welding rod steel and then ground to the proper surface and

sharpness. Stellite is added as the edge wears and each application is finished by grinding. The sloping back 50 of the bed knife is always bearing against the spout which is machine-finished to the same slope as that of the abutting surface of the knife. The hold bolt 36 is adapted to clamp the bed-knife 34 firmly in place at any particular level depending on the number of shims used. As shown in Fig. 2 and by dotted lines in Fig. 5, corresponding shims 52 may be inserted above the surface 38 of the bed knife 34 as the shims 46 are successively removed, so as to keep the weight of the spout on the bed knife.

15 By providing, for example, a supporting surface 32 having a 10° slope to the rear and similarly a forwardly sloping back supporting surface 48, a variation of $\frac{1}{2}$ " in chip length will be permitted by raising or lowering the bed knife 20 $1\frac{1}{2}$ ".

It will be seen that by the novel construction of the invention, there has been provided a wood chipper in which the bed knife will be firmly and solidly anchored and supported, but nevertheless easily accessible for quick retraction and insertion, and in which a single bed knife may be used in cutting chips of any desired length with a minimum of adjustments. Because of the ease and speed with which a dull knife may be replaced with a sharpened one, the machine need be shut down for a much shorter period for replacement or sharpening of the bed knife than in the case of the structures of the prior art.

35 While in the foregoing description and the accompanying drawings, I have illustrated a preferred embodiment of the invention, it will be understood that the same is capable of changes and modifications within the spirit and scope of 40 the appended claims.

I claim:

1. In a wood chipper having a rotating knife which cooperates with a stationary bed knife for chipping wood and an inclined spout for feeding logs downwardly to said cooperating knives, the combination comprising: a stationary base and a bed knife seat in said base for holding a stationary bed knife in operative relation to said rotating knife, said seat comprising a downwardly and rearwardly inclined seating surface 45 and a back wall surface inclined upwardly and forwardly from the inner end of said seating surface at an acute angle thereto to form a re-entrant recess facing the path of the rotating knife, said surfaces being adapted to engage and solidly support a bed knife having bottom and back surfaces inclined to each other at the same acute angle as the angle of intersection of the corresponding surfaces of said seat when such bed knife is seated in said seat whereby said bed knife may be adjusted toward the rotating knife solely by the insertion of shims positioned between the bottom surface of the bed knife and said seating surface.

65 2. In a wood chipper having a rotating knife which cooperates with a stationary bed knife for chipping wood and an inclined feed spout for feeding logs downwardly to said cooperating knives, the combination comprising: a stationary base, a bed knife seat in said base for holding a stationary bed knife in operative relation to said rotating knife, said seat comprising a downwardly and rearwardly inclined seating surface and a back wall surface inclined upwardly and forwardly from the inner end of said seating sur-

face at an acute angle thereto to form a re-entrant recess facing the path of the rotating knife, said surfaces being adapted to engage and solidly support a bed knife having bottom and back surfaces inclined to each other at the same acute angle as the angle of intersection of the corresponding surfaces of said seat when such bed knife is seated in said seat, whereby said bed knife may be adjusted toward the rotating knife solely by the insertion of shims between the bottom surface of the bed knife and said seating surface, said bracket being positioned on said base so that a portion thereof and the lower end portion of said spout will rest on portions of the upper surface of the bed knife when the latter is in seated position to subject the same to a vertical component of at least a portion of the weight of said spout to hold said bed knife firmly in said seat during chipping operations of said chipper.

3. Apparatus according to claim 2 in which said seating surface and said back wall surface extend laterally to a side wall of said base, thereby providing said re-entrant recess with an open end to permit insertion and withdrawal from seated position of said bed knife from one side of said base.

4. In a wood chipper having a rotating knife which cooperates with a stationary bed knife for chipping wood, the combination comprising: a stationary base, a bracket mounted on said base, an inclined feed spout held by said bracket for feeding logs into the path of the rotating knife, and a bed knife seat in said base, said seat comprising a downwardly and rearwardly inclined seating surface and a back wall surface inclined upwardly and forwardly from the inner end of said seating surface at an acute angle thereto to form a re-entrant recess facing the path of the rotating knife, said surfaces being adapted to engage and solidly support a bed knife having bottom and back surfaces inclined to each other at the same acute angle as the angle of intersection of the corresponding surfaces of said seat

when such bed knife is seated in said seat, whereby said bed knife may be adjusted toward the rotating knife solely by the insertion of shims between the bottom surface of the bed knife and said seating surface, said bracket being positioned on said base so that a portion thereof and the lower end portion of said spout will rest on portions of the upper surface of the bed knife when the latter is in seated position to subject the same to a vertical component of at least a portion of the weight of said spout to hold said bed knife firmly in said seat during chipping operations of said chipper.

5. Apparatus according to claim 4 in which said bracket is provided with jack screws bearing on said base for relieving the bed knife of the weight of said spout, and in which said seating surface and said back wall surface extend laterally to a side wall of said base, thereby providing said re-entrant recess with an open end to permit lateral insertion and withdrawal from seated position of said bed knife from one side of said base while so relieved of said weight.
